US00D798913S

(12) **United States Design Patent** (10) **Patent No.:** **US D798,913 S**
Whittaker et al. (45) **Date of Patent:** **** Oct. 3, 2017**

(54) **COMBINED MULCHING TOOTH AND DEPTH LIMITER**

(71) Applicant: **Beaver Mulching Inc.**, Red Deer (CA)

(72) Inventors: **Mark Robert Whittaker**, Rimby (CA); **Collin Andrew Watts**, Eckville (CA)

(73) Assignee: **Beaver Mulching Inc.**, Red Deer (CA)

(**) Term: **15 Years**

(21) Appl. No.: **29/553,828**

(22) Filed: **Feb. 4, 2016**

(51) LOC (10) Cl. **15-03**

(52) U.S. Cl.

USPC **D15/29; D15/28**

(58) **Field of Classification Search**

USPC ..... D15/11, 28, 29, 21, 19; 37/456, 452, 37/450, 446, 454, 449, 453, 455, 903; 403/379.5, DIG. 1; 111/152; 172/724, 172/730, 766, 770, 771, 721, 713, 699, 172/772

(57) **CLAIM**

The ornamental design for a combined mulching tooth and depth limiter, as shown and described.

DESCRIPTION

FIG. 1 is a top, front and left side perspective view of a combined mulching tooth and depth limiter showing my new design;

FIG. 2 is a rear view thereof;

FIG. 3 is a left side view thereof;

FIG. 4 is a front view thereof;

FIG. 5 is a right side view thereof;

FIG. 6 is a bottom plan view thereof; and,

FIG. 7 is a top plan view thereof.

1 Claim, 2 Drawing Sheets
